DESIGN FOR A FOLDABLE SERVING TABLE

Leo Lion, New York, N. Y.

Application July 15, 1944, Serial No. 114,409

Term of patent 14 years

(Cl. D33—14)

To all whom it may concern:

Be it known that I, Leo Lion, a citizen of no country, residing at New York, in the county of New York and State of New York, have invented a new, original, and ornamental Design for a Foldable Serving Table, of which the following is a specification, reference being had to the accompanying drawing, forming part thereof.

In the drawing,

Fig. 1 is a side perspective view of a foldable serving table showing my new design;

Fig. 2 is a side perspective view of said serving table in folded condition.

The lower shelf shown in Figure 1 has been omitted for convenience of illustration.

I claim:

The ornamental design for a foldable serving table, as shown.

LEO LION.
